METHOD OF OPERATING PLUNGER LIFT APPARATUS

Norman H. Ricker, Houston, Tex., assignor to Hughes Tool Company, Houston, Tex., a corporation of Texas

Application February 13, 1932, Serial No. 592,825

2 Claims. (Cl. 103—5)

My invention relates to the operation of plunger lift devices in wells having a small production only and where no appreciable amount of gas is produced in the well.

5 In deep wells whose daily production is small I contemplate obtaining a pressure differential between the interior of the eduction tube and the surface of the liquid in the well so that there will be sufficient excess of fluid pressure on said 10 liquid to raise a comparatively small load to the surface.

In doing this I allow full atmospheric pressure to be exerted on the liquid at the well bottom and then partially exhaust the air in the eduction tube above the liquid therein so that the 15 excess of air pressure below will be great enough to raise the plunger with a small load of liquid.

In the drawing Fig. 1 shows a side view, somewhat diagrammatic, of a well installation in which 20 my invention may be carried out.

Fig. 2 is a vertical section through the interior well equipment which is used.

In the usual plunger lift equipment the well eduction tube 1 extends from the surface downwardly within the casing 2. At the lower end the said tube has a strainer plug 3 which extends into the liquid to be pumped. Above the plug 3 is a stop 4 against which the valve stem 5 on the plunger 6 may strike to close the valve at the 30 lower end of its stroke.

The plunger is of common construction with a body 6 having a valve seat 7 against which the upwardly closing valve 8 may engage. Said valve is supported in open position by the support 9 at the lower end of the plunger.

The casing 2 may extend above the platform 10 of the derrick 11. The flow head 12 thereon, has an air inlet 13 which may have a foraminated strainer member 14 thereon to keep out foreign 40 matter. This inlet to the casing allows atmospheric pressure to be exerted in the well upon the liquid 15 therein.

The upper end of the eduction tube extends above the flow head and has a fluid tight fit with 45 the bonnet 16 thereof. A cap 17 closes the end of the tube.

The fluid outlet from the tube and flow head is shown at 18 leading to a closed container 19, the upper end of which is connected by a pipe 50 20 to an air pump 22. A pipe 21 at the lower end allows the liquid to discharge to the tank 23.

With this arrangement I am enabled to exert a suction or partial vacuum within the container

19 and the eduction tube 1 above the liquid, thus reducing the atmospheric pressure within the tube so that the air pressure upon the lower side of the plunger in the well tube will be sufficient to raise the plunger 6 with a small load of liquid upwardly in the tube to the surface. The liquid will there be discharged to the container 19 and the plunger will move into the closed upper end of the tube 1, where the valve will open and the plunger will drop back to repeat its operation. 10

The manner in which the device works is not materially different from the working of the usual plunger lift installation with the exception that the pressure differential necessary to lift the plunger and its load is obtained by decreasing the pressure in the tube above the load rather than by increasing the pressure below the load. This idea is of value particularly where the rate of production from a well is small, although its use is manifestly not confined to such 20 wells. It will make it possible, however, for the liquid to flow into the well unimpeded by a back pressure thereon from the pressure fluid ordinarily employed, and thus will enable said old wells to be pumped where otherwise it would be difficult to do so. In Fig. 2 the plunger is falling, when the valve stem 5 engages the stop 4 the valve will close, shutting off the load of liquid above it from the liquid below. The liquid in the well drops back and the atmospheric pressure entering the openings at 3 below the plunger exerts a pressure on the plunger and its load in excess of the reduced pressure above the plunger and the plunger thus is caused to move upwardly with its load to the surface. 30

What I claim as new is:

1. A method of raising liquid from wells having an eduction tube therein comprising introducing a barrier below a load of liquid in said tube, reducing the air pressure in said tube above 40 said load, providing for full atmospheric pressure on the liquid outside said tube and below said barrier, and thus raising said barrier with its load by atmospheric pressure.

2. A method of raising liquid from wells having an eduction tube therein comprising introducing a barrier below a load of liquid in said tube, withdrawing air from said tube above said load, and employing the excess of pressure due to atmosphere exerted in the well below said barrier to 50 raise said barrier and said load in said tube.

NORMAN H. RICKER.
